UNITED STATES PATENT OFFICE.

MARY ELIZABETH WHITTEMORE, OF MOUNT VERNON, IOWA.

TAPE-NEEDLE.

SPECIFICATION forming part of Letters Patent No. 705,800, dated July 29, 1902.

Application filed November 5, 1901. Serial No. 81,199. (No model.)

To all whom it may concern:

Be it known that I, MARY ELIZABETH WHITTEMORE, a citizen of the United States, residing at Mount Vernon, in the county of 5 Linn and State of Iowa, have invented a new and useful Needle for Tapes, Ribbons, and Cords, of which the following is a specification.

My object is to provide an improved tape-needle especially adapted for drawing a tape, ribbon, or other flat lengths of material through casings and open or reticulated woven fabrics, as required to facilitate such work and to prevent the annoyances incident to 15 tapes or ribbons becoming twisted in the progress of such labor.

A further object is to adapt the same needle for drawing a cord through the hems of curtains and other articles made of woven 20 fabrics, as required for shirring the material.

My invention consists in the needle adapted for such special uses and constructed as hereinafter set forth, pointed out in my claim, and illustrated in the accompanying drawings, 25 in which—

Figure 1 is a diagrammatical view of the needle. Fig. 2 is a transverse sectional view on the line $\alpha\alpha$ of Fig. 1, showing the contour of the surface on each side of the needle. Fig. 30 3 is a longitudinal sectional view on a central line that shows the manner of forming teeth at the large end and the tapering to the small end. Fig. 4 shows a ribbon fastened to the needle and the needle inserted in a 35 piece of woven fabric, as required for drawing the ribbon therethrough.

The letter A designates the large body or head portion, and B the small tapering and pointed end, of a needle preferably made of 40 steel by means of dies and a press or in any suitable way. It is obvious it may vary in

size as desired and that it can be made of aluminium, brass, or other suitable material. An elongated eye c is formed in the large end to extend transversely to admit the end of a 45 tape or ribbon and a perforation d close to the eye to admit the end of a cord. Teeth f for biting fast to the end of a tape or ribbon are formed integral at the large end of the needle by cutting V-shaped incisions in the 50 metal and then bending the free pointed ends outward to project outward at an angle relative to the surface of the needle, as shown in Fig. 3, and to be adapted to fasten the end of a tape or ribbon thereto after it has been 55 passed through the eye c and doubled over and pressed on the points of the teeth, as required to retain the tape flat on the needle.

The needle is preferably thicker along its longitudinal central line than at its edges 60 and its surfaces convex; but it is obvious that it may be flat-faced.

Having thus described the purpose and construction of my invention, its practical operation and utility will be readily understood by persons familiar with the art to which it pertains, and

What I claim as new, and desire to secure by Letters Patent, is—

A needle made of a single piece of sheet 70 metal, wide at one end and tapering to a point at its other end and provided with a transverse eye at its large end, teeth near the eye and projecting toward the wide end and outward relative to the surface of the needle and 75 a perforation near the center portion of the eye, to operate in the manner set forth for the purposes stated.

MARY ELIZABETH WHITTEMORE.
